C. S. PELTON

HEATER FOR MOTOR PROPELLED VEHICLES

Filed May 8, 1920

Inventor:
Clyde S. Pelton
By Hull Smith Brock & West

Atty.

UNITED STATES PATENT OFFICE.

CLYDE S. PELTON, OF CLEVELAND HEIGHTS, OHIO, ASSIGNOR TO THE PERFECTION HEATER AND MANUFACTURING COMPANY, OF CLEVELAND, OHIO, A CORPORATION OF OHIO.

HEATER FOR MOTOR-PROPELLED VEHICLES.

Application filed May 8, 1920. Serial No. 379,818.

To all whom it may concern:

Be it known that I, CLYDE S. PELTON, a citizen of the United States, residing at Cleveland Heights, in the county of Cuyahoga and State of Ohio, have invented a certain new and useful Improvement in Heaters for Motor-Propelled Vehicles, of which the following is a full, clear, and exact description, reference being had to the accompanying drawings.

This invention relates to heaters for motor propelled vehicles wherein the hot exhaust gases from the motor are employed to heat the passenger compartment. The particular heater herein described and claimed has been developed for use with motors of the type provided with twin exhaust pipes, and the objects of the invention are the provision of a simple, compact and efficient type 20 of heater which can be connected to such twin exhaust pipes so as to heat the air in the car without at the same time throwing the motor out of balance; the provision of a simple, inexpensive, and attractive heater; 25 while further objects and advantages of the invention will become apparent as the description proceeds.

One embodiment of the invention is shown in the accompanying drawings in which Fig. 1 is a top plan view of the complete heater, certain parts being shown as broken away; Fig. 2 is a longitudinal sectional view through the device shown in Fig. 1; Fig. 3 is a cross sectional view corresponding to the broken line 3-3 of Fig. 2; Fig. 4 is a perspective view showing the relation of the heater to twin exhaust pipes arranged on opposite sides of the car; and Fig. 5 is a perspective view of the heater arrangement when the exhaust pipes are arranged on the same side of the car.

Describing the parts by reference characters 1-1 represent a pair of similar hollow headers, each being divided into two chambers by a partition 2. Each chamber has a port opening through the bottom of the header, and also a plurality of sockets opening through that side which faces the other headers and receiving the ends of the radiator pipes 3-3. In the present embodiment,

each chamber is formed with two sockets, four radiator pipes in all being employed, but the number may be greater or smaller as desired excepting that it is preferable to have equal numbers of pipes communicating 55 with the different chambers. The headers are held in place by means of suitable bolts 4-4 which project through certain of the pipes.

The radiator is located in a suitable casting such as the oblong pan 5 adapted to be set in a hole in the car floor, and covered by a perforated floor plate 6. The plate is here shown as clamped upon the top flange of the pan by means of screws 7-7, and the lower face of each heater is also shown as having shoulders 8-8 which rest on the pan and are secured thereto by screws 9. The bottom of the pan is formed near its ends with apertures which register with the nipples 10-10 which surround the ports and receive the pipe connections which lead to the exhaust pipe. Plain elbows 11-11 are shown at one end in combination with elbows 12-12 at the other end, the latter arranged to cross each other. At one end is shown a vertical rock shaft 15 connected to an adjusting lever 16 and operating arm 17 adapted to be connected to a suitable kind of valve by which the flow of exhaust gases can be 80 regulated.

The radiator is arranged transversely of the car, and when the exhaust pipes are arranged on opposite sides of the car as shown in Fig. 4 the inlet conduits 18-18 are connected at opposite headers to chambers which communicate with different sets of pipes so that the gases after passing through the radiator are discharged upon opposite sides of the vehicle from their point of origin. They may be either discharged directly into the atmosphere or led to some suitable place of escape by the pipes 19-19. In case both exhaust pipes are disposed upon the same side of the vehicle as shown in Fig. 5 they are preferably connected to the same header, in which event the gas flow is in the same direction in the two sets of pipes and the spent gases are discharged from the opposite header.

It will be understood that many changes in detail can be made within the scope of my invention.

Having thus described my invention, what I claim is:

1. In an automobile, the combination with an engine having two independent exhaust pipes located one at each side of the car, of a radiator having two parallel sets of heating pipes located side by side and extending transversely of the car, one set of pipes being operatively connected to each exhaust pipe and discharging the waste gas at the opposite side of the car.
2. In an automobile, the combination with two independent exhaust pipes of an engine, of a radiator having two parallel sets of heating pipes located side by side, each set

of heating pipes being operatively connected at one end to one of the exhaust pipes and discharging the exhaust gas at its opposite end.

3. In an automobile, the combination with two independent exhaust pipes of an engine, of a casing, two sets of parallel pipes inside of said casing arranged side by side and extending from end to end thereof, headers attached to the ends of said pipes having independent inlet and outlet chambers for the respective sets of pipes, and means connecting each inlet chamber to one of said exhaust pipes.

In testimony whereof, I hereunto affix my signature.

CLYDE S. PELTON.
